Primary Examiner — Robert M Spear*Assistant Examiner* — Ryan Harvey(74) Attorney, Agent, or Firm — Inventive Patent Law P.C.; Jim H. Salter(57) CLAIM

The ornamental design for a gymnastics mat, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever. FIG. 1 is a top view of a gymnastics mat, showing my new design;

FIG. 2 is a bottom view of the gymnastics mat; and,

FIG. 3 is a side view of the gymnastics mat.

1 Claim, 2 Drawing Sheets(56)
